UNITED STATES PATENT OFFICE.

EDMOND L. BEAN, OF HYDESVILLE, CALIFORNIA

SEAT-SPRING.

No. 921,942.

Specification of Letters Patent. Patented May 18, 1909.

Application filed July 13, 1908. Serial No. 443,221.

To all whom it may concern:

Be it known that I, EDMOND L. BEAN, a citizen of the United States, residing at Hydesville, in the county of Humboldt and State of California, have invented certain new and useful Improvements in Seat-Springs, of which the following is a specification, reference being had to the accompanying drawings.

10 This invention relates to improvements in wagon seats and more particularly to springs therefor.

The object of the invention is to improve the construction of seat springs and to provide one which will occupy but little space and not project beyond the front and rear edges of the seat and be in the way of the occupant thereof, nor inwardly beneath the central part of the seat and interfere with the 20 loading of the wagon.

With the above and other objects in view, as will hereinafter more fully appear, the invention consists of the novel features of construction and the combination and arrangement of parts described in the following specification and illustrated in the accompanying drawings, in which—

Figure 1 is a front elevation of the improved seat; Fig. 2 is a side or end elevation 30 of the same; Fig. 3 is a vertical transverse section through the spring; and Fig. 4 is a horizontal section taken on the plane indicated by the line 4—4 in Fig. 3.

The improved seat spring is designed to 35 take the place of the usual bow or leaf springs now in general use on farm wagons, but it may be adapted for use on carriages, buggies and other vehicles. The spring comprises an oblong coil 1 constructed of square 40 spring steel and upper and lower bars 2, 3 between which the spring is arranged and to which its ends are effectively clamped by U-shaped bolts or clips 4. The improved springs are adapted to take the place of the 45 ordinary leaf springs above mentioned, and the coils 1 are therefore made comparatively narrow and of slightly less length than the width of the seat S. Said springs and also their fastening bars 2, 3 are made of less 50 width than the upper edges of the sides of the wagon body so that they will not project into or above the space within the wagon body, thereby permitting a portion of the space in the wagon body beneath the seat to be loaded up to and above the plane of the top of the

body. By constructing the springs in this manner they will be very little broader than the old style springs and will not project beyond the front and rear edges of the seat and will therefore not interfere with the loading 60 of the wagon or the driver climbing up upon the seat and descending from the same, as is the case with the old style leaf springs. As above explained, this construction leaves the space beneath the central part of the seat 65 open and permits a high load to be placed at the front end of the wagon body. By making the coil springs 1 of square steel their ends may be effectively clamped to the upper and lower bars or boards 2, 3 and side springing 70 will be overcome to a certain extent, and particularly when the spring is made rectangular in cross section and its widest part is disposed laterally or horizontally. The upper and lower bars 2, 3 are secured to the seat S 75 and the wagon body W by bolts 5 arranged adjacent to the center of said bars, as clearly shown in the drawings. Cleats 6 may also be provided upon the lower bars 3 to engage the inner face of the sides of the wagon body 80 and relieve the bolts 5 of a part of the strain.

From the foregoing it will be seen that the improved spring is simple, strong, durable and practical in construction and that it is exceedingly compact and will effectively 85 overcome the objections to the old style leaf springs.

Having thus described the invention what is claimed is:

The combination with a vehicle body having a seat, of bars secured to the underside of said seat adjacent to the ends thereof, bars secured to the sideboards of the vehicle body and disposed in spaced relation to the bars upon the seat, and springs disposed between 90 the bars and extending longitudinally of the vehicle body, said springs each being formed from a single piece of metal square cross sectionally, said metal being bent to provide elongated convolutions arranged in parallel 95 spaced relation to each other, the side portions of the convolutions of the springs extending longitudinally of the side boards of the vehicle body.

In testimony, whereof I hereunto affix my 105 signature in the presence of two witnesses.

EDMOND L. BEAN.
